PIMENTO CORING MACHINE HAVING A ROTATABLE CORING HEAD, INCLUDING AN ANNULAR SERIES OF RECIPROCAL ROTATABLE CORING TUBES

Earl White, Moultrie, Ga.

Application October 18, 1950, Serial No. 190,778

9 Claims. (Cl. 146—52)

1

Generically this invention relates to an automatic machine for removing the cores from fruits or vegetables, but is more particularly directed to such a machine for removing the cores from and otherwise operating upon pimento peppers, and the like.

The manner and means heretofore in use for removing the cores of peppers has proven not only comparatively slow and laborious but otherwise unsatisfactory, and, therefore, one of the principal objects of this invention is the provision of an automatic pepper coring and finishing machine capable of not only rapidly removing the cores, but also effecting the removal of other portions in a finishing operation.

Another important object of this invention is the provision of a pepper coring machine comprising a rotatable head including an annular series of reciprocal rotatable coring tubes, an endless conveyor chain having pepper bearing cups adapted to pass beneath the rotatable head for effecting removal of the core from each pepper as it passes thereunder, and additional novel means in connection with the respective cups for removing the bloom end of the pepper and at substantially the same time a coring tube is removing the core from the opposite end thereof.

A further important object of this invention is the provision of a rotatable head including an annular series of reciprocating rotatable coring tubes, and an endless conveyor chain structure including a plurality of pepper carrying cups adapted to travel thereunder in operative relation with said tubes, and additional novel means in advance of the tubes for removing the stem portions of the peppers so that the pods will not be tilted or out of position as they pass under the coring tubes.

A further important object of this invention is the provision of a coring machine of this character provided with a series of rotatable coring tubes including means operable within each tube and adapted when the tube has reached its insertible coring limit within the pepper to grippingly engage and hold the core during withdrawal of the tube and core from the pepper, and means then predeterminedly operable to release said core holding means to permit discharge of the core from the tube.

An important object of this invention is the provision of a pepper or the like coring machine of this character comprising a rotatable annular series of coring tubes, each tube including pivotally mounted fingers extending therein operable

2

to grippingly engage the core of a pepper within the tube as it is separated from the pepper and to hold it until the tube has reached a predetermined position in its rotary travel, the fingers then being operable to their initial open position, and at which time the core is ejected from the tube.

Another important object of this invention is the provision of a pepper coring machine of this character comprising a rotatable annular series of coring tubes, each tube being independently rotatable, core engaging means within the tubes, means adapted to actuate said engaging means into gripping contact with the core as it is separated from the pepper, and to hold it until the tube has advanced to a predetermined position, then operable to permit release of said gripping means, and additionally operable to expel said core from the tube.

Another important object of this invention is the provision of a coring machine of this character including a coring tube structure comprising novel means for operating the tube in pepper injecting and core separating direction, means within said tube for gripping the core as it is separated from the pepper, and reciprocal cam means for actuating said gripping means to hold the core as the tube is withdrawn, said cam means operating to release the gripping means at the proper time, and then operating as a plunger to eject the core.

Another important object of this invention is the provision of a pepper coring machine comprising an endless chain conveyor having a series of cups operatively connected therewith, each cup adapted to contain a pepper or the like to be cored, a coring mechanism comprising a rotatable series of reciprocal coring tubes, and means in connection with said conveyor structure operable to effect vertical adjustment thereof to position the same in operative relation with respect to the coring tubes in accordance with peppers of different heights.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a side elevation of my improved coring machine.

Fig. 2 is an enlarged front end elevation, showing the cored article removing depending chain portion at the rear end of the machine.

Fig. 3 is an enlarged cross sectional view of one of the coring tubes and operating connections with parts in side elevation.

Fig. 4 is an enlarged sectional view of one of the cups, fragmentary side elevation of the conveyor chain with parts broken away, and the pepper bloom and removing device in elevation.

Fig. 5 is an enlarged sectional view through the driving gear arrangement with the drive shafts and parts in elevation.

Fig. 6 is an enlarged perspective view of one of the coring tube cam rods with its finger control rod, and frame section mounting therefor.

Fig. 7 is an enlarged elevational view of one of the coring tubes and core engaging finger mounting.

Fig. 8 is an enlarged transverse sectional view through the conveyor chain and track, taken on the line 8-8 of Fig. 1, showing one of the cups and its track engaging portions in elevation.

In the illustrated embodiment characterizing this invention there is shown a supporting frame structure 1 comprising pairs of vertical standards 2 and 3 connected at their upper ends by frame structure 4 and at their lower ends by a base frame 5.

Mounted on and secured to the frame plate or structure 4 are the upright supporting standards 6 and 7, the end standard 6 being further secured by a brace 8 anchored by a bolt or like fastening means 9. Suitably journaled in said standards 6 and 7 is a drive shaft 10, on one end of which is suitably secured bevel gear 11. Also mounted thereon is a drive sprocket wheel 12. Mounted rearwardly from sprocket 12 is a motor 13 (Figs. 1 and 2), having a drive sprocket 14 connected to sprocket 12 by sprocket chain 15. Member 4 extends beyond the frame member 2 to which it is secured by brace 16, as desired.

Extending through top member 4 and supported in thrust bearing 17, the base 18 of which is supported by base member 5, is the main drive shaft 19 which extends through the coring head structure A. The upper end of said shaft 19 extends above frame member 4 and is journaled in bearing 20, and suitably mounted on and secured to the upper end of said shaft is a bevel gear 21 and meshing with bevel gear 11 on motor drive shaft 10.

Within the frame structure 22 formed by the circular series of frame members 23 and connected by the rib members 24 is an upper cam track 26 and a lower cam track 27, mounted on and suitably secured to rods 25 which extend through the top frame member 4 and are supportingly secured by nuts 28. Reciprocally mounted in each of the frame members 23 is a coring tube supporting cam rod 29.

Mounted on a pin 30 at the top of each rod 29 (in the present instance six) is a cam roller 31 off-set with respect to the said rod and adapted to travel in the upper eccentric or cam track 26 for a purpose directly more fully appearing.

Likewise, a finger control and core ejecting rod 32 is mounted within rod 29 and at its upper end is formed with a lateral extension 33 adapted to project through registering slots 34 formed in rod 29 and its frame section 23 and on the end of which is mounted a cam roller 35 adapted to travel in the lower cam track or eccentric 27 to effect relative reciprocation of the finger control rod 32 with respect to that of its rod 29. Mounted on each of the coring tube cam rods 29 flush with the shoulder 36 of the reduced end 37 is a fixed coring tube head plate 38. Extending through opposite sides of head plate 38 are de-

pending rods 39 adjustably secured by nuts 40 and mounted on said rods seating is a hold-down bar or plate 41, and mounted on said bolts and seating on said bar are compression springs 42, the upper ends of said springs seating in the lower ends of the tubes 43, and the upper end of said tubes seating against the plate 32. The resiliently mounted hold-down plate 41 is adapted to prevent upward movement of the peppers incident to the withdrawal of the coring tubes following their coring action and contributes to maintaining the peppers in proper position during the coring operation.

Suitably mounted on the reduced end 37 of each of the cam rods 29 and rotatably mounted on ball bearings 44, is a coring tube gear 45 adapted to mesh with the large gear 46. Said gear 45 is formed with a hub portion 47 projecting within the upper end of the coring tube 43 and is fixedly secured thereto by screws or other fastening means 49. The lower end of said tube extends through and beyond the hold-down bar 41. It will be noted that the head A is mounted on and splined or otherwise attached to the main drive shaft 19, and as it is rotated clockwise by said shaft, the coring tube assemblies B will be rotated about the large gear 46 and, since the coring tube gears 45 are in mesh with said large gear, the respective tubes 43 will be rotated about their axes as they are rotated by the movement of said head about its axis and travel around and reciprocally over the face of said large gear 46. The coring tubes 43 (Figs. 3 and 7) are formed with cutting edges 48'.

It is important that irrespective of whether the peppers or other articles are in a firm or soft state, that the cores be removed cleanly and without damage to the article being cored, and, therefore, it is necessary that the large gear 46 be rotated clockwise which causes the coring tubes 43 to rotate anti-clockwise at a substantially rapid speed and in a direction opposite to that of said head A. The speed of said coring tubes may be varied by changing the speed of the large gear if desired in accordance with different articles being cored.

Each of the coring tubes 43 is formed adjacent its upper end with diametrically opposed slots 50, and is formed adjacent the lower edge of each slot with a pair of ears 51. A pair of core-engaging fingers C is mounted in each tube and formed with an arcuate projection 52 engageable between ears 51 and rotatably mounted on a pin or bolt 53 extending through the registering openings of the ears 51 and projections 52. Each finger is formed with a widened head 54 projecting upwardly and outwardly from the projection 52 and upwardly and downwardly, intersecting with the cam faces 55 which extend at an angle upwardly and inwardly from a point adjacent the pivotal post 53. Said heads 54 of the fingers normally project upwardly beyond the tubes 43 and substantially at their widened portions, they are formed with arcuate slots 56 in which is mounted a coil spring 57 which normally maintains the fingers in substantially overlying contact with the inner wall surface of the tube 43. The cam finger control rod 32 extends downwardly through the coring tube gear 45 to a point substantially intermediate the pivot bolts 53 and substantially at the lower ends of the cam faces 55. Suitably mounted on the end of said rod is the finger-operating annular cam and core plunger head 58. Said head 58 is of a greater diameter than the normal distance between the upper ends of the

cam faces 55, so that in operation, as the tube is projected into the pepper D during the coring operation the rod 32 is raised by the cam roller 35 reaching a predetermined point in its cam track 27 causing cam head 58 to engage the cam surfaces 55 spreading the heads 54 against the action of the spring 57, and moving the fingers C to the positions shown in dash lines as at 59, to grippingly engage and hold the core until the tube has reached a predetermined point in its conveyed travel or on the far side of the rotary head A, whereupon the cam rod 32 is moved with its plunger head 58 downwardly, permitting the fingers by the action of the spring 37 to assume their initial expanded positions and the plunger head at the same time moving downwardly expelling the core from the tube as will hereinafter be more fully explained.

Referring more particularly to the endless pepper conveyor E and associated parts it will be noted that a pair of parallel spaced tracks 60 is adapted to support the traveling conveyor E. Each of the said tracks comprises a pair of spaced angle members 61, the vertical portions 62 of which are spaced apart to house and permit the free travel of the conveyor chain E, and the horizontal aligned portions 63 of which are adapted to be supported by the frame standards 64 interconnecting said members 61 and frame members 65 which are suitably connected at one end to the standards 3 and in their other ends with the rear frame posts 66, the standards 64, frame members 65, and end posts 66 may be connected by suitable cross members 67, as desired. The posts 66 are further connected by a cross member 68 on which is suitably mounted central of its length, the rear end vertically disposed sprocket 69 journaled on axle 70.

Mounted at the front end of the machine, as directly more fully explained, is a horizontally disposed sprocket 71, and adapted to travel in said tracks 60 and over sprockets 71 and 69 is an endless conveyor chain E comprising semi-universally interconnected links 72 and 73. Mounted on said chain E are a plurality of cone-shaped pepper carrying cups 74 substantially conforming to the shape of the peppers. Each of said cups is formed, in the present instance, with an integral base portion 75, adapted to seat on the upper face of a link as shown in Fig. 4, and connected to the links by screws or other suitable fastening means 76, the base and link being formed with registering bores 77 and 78, respectively, in which is journaled shaft 79 on the upper end of which is suitably mounted and secured a rotatable burr member or the like 80 having a toothed or roughened surface 81 adapted to remove the flower end of the pepper D when the latter is being carried by the cup 74 as will be directly more fully explained. The lower end of said shaft 79 projects beyond the chain E and on which is suitably mounted a pulley 82 formed with a concave surface 83. In order not to create a vacuum by the placing of the peppers in the cups 74, said cups are formed with a series of spaced openings 74'. Also the cup base 75 is formed with integral wing portions 75' extending at right angles thereto and constituting stabilizing conveyor and cup supporting members adapted for slidable travel over the dual track surfaces of members 63 as will be apparent.

Mounted on the posts 66 are the bearings 84 in which is journaled a shaft 85 and mounted on the shaft are the sprockets 86 in alignment with the tracks 60 over which is adapted to travel 75 porting means and mounted for vertical adjust-

the endless chain E, said chain extending downwardly from said sprockets and over rear sprocket 69 so as to effect the removal of the cored peppers as will directly more fully appear.

The tracks 60 terminate at their front ends at a point short of the standards 2 and are supported on cross bar 87 suitably interconnecting the vertical members 88, which latter are also connected by the cross bar 89. Said vertical members 88 are seated on and secured to braces 90, said braces extending upwardly and rearwardly and suitably connected at their upper ends to the track members 61 of tracks 60, or by a cross member interconnecting said tracks, if desired. Said endless chain E extends forwardly beyond members 88 and the end of tracks 60 and around sprocket 71, having vertical slidable connection with its tubular shaft, the axis of which is coincident with that of the axis of the vertical drive shaft 19, and said sprocket is rotatably supported by a cradle structure 91 including arms 92 pivotally connected thereto as at 93, the rear ends of said arms extending over cross bar 89 and under cross bar 87 to which they are suitably connected. The arms 88 are provided with rack teeth 94 adapted to mesh with pinions 95 mounted on shaft 96 journaled in bearings 97 suitably mounted on and connected to angle bars 98 mounted on and connected to frame standards 2 and 3. Splined or otherwise mounted at the free end of shaft 96 is a crank handle 99, and bars 98 are connected to frame members 2 and 3 by bolts 100 or other suitable fastening means.

It will be noted that the above front and track supporting structure is operable by actuation of the handle 99 to effect slight vertical adjustment of the front portion of track 60, conveyor chain E, cradle structure 91 and sprocket 71, in accordance with different sized peppers, so that the coring tubes 48 can effect the decoring of the peppers as they reach coring position. Thus it will be noted that the sprocket 71 and the tracks 60 are adapted to normally support the chain E in a plane to permit the cups with the peppers D therein to pass beneath the coring tube 48 and hold-down plate 41 so that said peppers will be positioned in underlying operative relation with respect to said rotating coring tubes, Figs. 1 and 2. Therefore it was necessary to provide for the vertical adjustment of the forward portion of cup carrying conveyor chain E to compensate for peppers extending different heights above the cups.

Suitably mounted on the cradle structure 91 below the sprocket 71 of the conveyor chain E, and correspondingly curved at the front (Fig. 2) is a rubber covered or roughened surface rod member 83', extending rearwardly at the right (Fig. 1), and adapted to engage over the pulleys 82 and rotatably actuate the burrs 80 to remove the bloom ends of the peppers D as they immediately approach the coring tube mechanism or coring head assembly. It will be apparent that being mounted on said cradle structure, said rod will at all times be operatively positioned with respect to the pulleys 82.

The front vertical frame standards 2 are interconnected in approximate alignment with the shaft 96 by the cross angle bars 101, and the frame standards 3 are connected in alignment with bars 101 by angle bar 102. Mounted on the bars 101 and 102 are the angle bars 103 mounted adjacent the vertical standards 88 and brace structure 90. A bracket or frame structure 104 is suitably mounted on standard 3 or other supporting means and mounted for vertical adjust-

ment thereon is a small motor 105 connected thereto by base 105'. Said motor is connected to a source of power and on the drive shaft 106 of which is mounted a saw 107 or the like in vertical alignment with the right hand track and conveyor feeding line of cups 14 (looking from the front end in the direction of the arrows 8-8') and in operative relation above the feeding line of peppers D to remove the stems therefrom in advance of the coring action of the tubes 48 rotatably carried by the coring head A. The motor 105 is adjustable on base 105' or the saw 107 may be vertically adjustable on its shaft 106 in accordance with the height of the particular peppers being cored.

Following the coring operation the cored peppers are delivered from the coring head by the left hand line of cups and during its vertical descent from the sprocket 86 the cored peppers being discharged by gravity or dumped out of the said cups onto a conveyor or into a suitable container (not shown). In being removed from the cups the peppers usually leave fragments thereof adhering to their interior walls, and, therefore, to prevent additional adherence when a succeeding pepper is placed in a cup and its normal height increased so that the saw 107 will cut into said pepper, a spray mechanism 108 shown in Fig. 1, is provided and positioned in alignment with the vertically ascending return line of empty cups, so as to direct a strong water spray into said cups to insure non-stickable and clean interiors to receive the succeeding peppers for coring as in the first instance.

The driving arrangement will now be described. The main drive is from motor 13 through chain 15 to shaft 10, beveled gear 11, beveled gear 21 and main drive shaft 19 to coring head A, revolving said head clockwise as shown in Fig. 2. The remaining driving and gear arrangement from shaft 19 is shown on Fig. 5, which includes the main drive shaft 19 on which is mounted the drive gear 109, and an auxiliary or idler shaft 110 with its lower end supported in thrust bearing 111 seating on the frame base 5 and its upper end journaled in bearing 112 suitably secured to members 101. Mounted on shaft 110 are the gears 113, 114 and 115. The gear 109 meshes with gear 113 driving shaft 110 anti-clockwise and through gear 114 drives gear 116 and the hollow tubular shaft 117 on which it is mounted, clockwise. Said shaft 117 is adapted to drive the large gear 46. Gear 115 on shaft 110 meshes with gear 118 secured to the lower end of the hollow tubular shaft 119, which loosely telescopes shaft 117, and is adapted to drive clockwise the conveyor drive sprocket 71. Suitably secured to the sprocket 71 is a hollow drive sleeve portion 120 into which the upper end of shaft portion 119 extends. The telescoping end of shaft 119 is formed with diametrically opposed slots through which extend pins or the like 121, carried by sleeve portion 120, and by means of which construction the vertical adjustment of sprocket 71 and conveyor E is permitted. If desired the sleeve can be slotted and the pins carried by shaft 119. Said large gear 46 may be mounted on the upper face of a ball bearing structure and the lower face fixedly attached to shaft 19, whereby said gear is rotatably supported and the enlarged portion 122 of shaft 117 is connected at its upper end to the under surface of said gear 46 which gear is rotated by the shaft 117, said enlarged portion 122 constituting a housing for said bearing.

While the operation of the device would appear to be clear from the above description, it might be well to further state, that the peppers or other articles D to be cored are manually placed in the cups of the conveyor moving feeding line in advance of the stem cutter 107 which severs the stems, and as the cup carrying the article approaches the coring mechanism the fixed rod 83' engages and effects rotation of pulley 82, rotating burr 80 removing the lower end of the article, or bloom end if it is a pimiento pepper. As each succeeding cup begins its arcuate travel in consonance with that of the registering coring tube, said tube is impelled downwardly by the action of its cam rod roller in cam track or eccentric 26, and begins its coring movement into the article and which completes its downward coring limit as it reaches the center point of its arcuate travel at the front of the machine (Fig. 2), and at which point it begins its receding movement by the action of its ascending cam roller in upper track 23, and at the same time the cam roller 35 on cam rod 32 moving upwardly in lower cam track 27 causes the cam-plunger head 58 to engage the cam faces 55, moving fingers C into core holding position as at 59. During the further arcuate travel of the coring head A and tube 48, and just before said tube begins its movement out of alignment with the cored article and the delivery conveyor line, said core is completely removed from the pepper or like cored article, and as it reaches complete disalignment, the cam plunger head is moved downwardly out of engagement with cam faces 55 expelling the core, by reason of the descending travel of cam roller 35, and the fingers C are returned to their normal expanded position (Fig. 3) by the action of spring 57, and the plunger head 58 is returned to its normal inoperative position (Fig. 3), where it remains until the coring tube has rotatably moved with the coring head to begin another coring cycle. Following the complete removal of the core, as above described, the cored articles are carried by the conveyor to the descending line at the far side (Fig. 1), and gravitationally removed or dumped onto a traveling conveyor or into a receptacle (not shown). As the empty cups move up the ascending portion of the feeding conveyor line they are subjected by the spray device 108 (Fig. 1) to a strong water spray which removes any remaining fragments of the cored articles and thoroughly cleanses the interiors of the cups for the repeated reception of articles to be cored as in the first instance.

While the construction and operation of the present invention has been designed more particularly for the coring of pimiento peppers, it is equally adapted to the coring of other articles, and it will be apparent that I have provided a coring machine embodying a compact rotatable coring head including a series of vertically reciprocating and rotatable coring tubes, simplified operating means therefor, including means for effecting rotation of said head and tubes in one direction, and additionally operating said respective tubes in an opposite direction, and additional features operable in a continuous operating cycle to effect the removal of the projecting stems and the bloom end, in the case of peppers, thereby eliminating manual steps, and not only reducing operating costs but increasing the cored output, said coring machine comprising comparatively few parts, readily assembled, manufactureable at a reasonable cost, and efficient for the purposes intended.

Although in practice I have found that the form of my invention illustrated in the accompanying drawings and referred to in the above description as the preferred embodiment, is the most efficient and practical, yet realizing that conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

1. A pepper or the like coring machine comprising an endless conveyor including a series of pepper carrying cups, each cup adapted to contain a pepper with the bloom end down, means in connection with the respective cups adapted to remove the bloom end of the pepper carried by the cup, said means comprising a rotary burr at the bottom of each cup, each cup being substantially shaped to embracingly receive the bloom end of a pepper, a coring device positioned adjacent to and above the cups and adapted to penetrate the pepper within each of the cups for decoring purposes, the said coring device including a resiliently mounted hold-down element engaging the pepper as the pepper approaches the coring device, and means adapted to actuate said bloom end removing burr while the pepper is engaged by the hold-down element and as it is approaching the coring device.

2. A machine for coring peppers and the like comprising an endless conveyor including a series of pepper carrying cups, each cup adapted to embracingly contain a pepper with the stem exposed and to bring the pepper into operative relation with respect to a coring device, a cutting device adapted to remove the stems from the peppers, a burr device positioned in the bottom of each cup adapted to remove the bloom end of the pepper, frictionally-operated means for rotatively operating said burr device as it approaches the coring device, said coring device including resiliently mounted hold-down means for engaging the pepper, a rotary coring cutter positioned adjacent to and above the peppers contained in the cups, and means for downwardly actuating the coring cutter for causing it to enter the pepper within each cup for decoring purposes, means for actuating the conveyor to successively position each cup in operative relation with respect to said cutting device for the stems to remove successive stems in advance of the decoring device and to position the cup into operative relation with respect to the burr operating means to remove said bloom end as the cup approaches the coring device, the said hold-down means engaging the pepper as the burr device operates on the bloom end of the pepper as each pepper and cup approaches the rotary coring cutter but prior to engagement of each pepper with the said rotary coring cutter.

3. A machine for coring vegetables, and the like, certain of which have upwardly projecting stems, said machine comprising a coring mechanism, an endless conveyor including a series of cups disposed adjacent to the coring mechanism and positioned beneath the same, each cup being substantially shaped to embracingly receive the bloom end of an article to be cored with its stem exposed and means for actuating said conveyor to successively bring an article to be cored into

operative relation with respect to said coring mechanism, a rotary burr device at the bottom of each cup, and means adjacent to the coring mechanism adapted to effect rotation of said burr device to remove the lower end of the article as it immediately approaches said coring mechanism, the said coring mechanism including a resiliently mounted hold-down plate engaging the article, and a rotary coring cutter having its operative cutting edge approximately axially disposed relative to the hold-down plate and projecting for a short distance therethrough, the hold-down plate engaging the article while the burr device is acting thereon immediately preceding engagement of the article and the coring cutter.

4. A pepper coring machine comprising in combination, an endless conveyor, a series of pepper-carrying cups operatively connected with the conveyor for receiving peppers with their bloom ends downward, the said cups being shaped to embracingly hold the bloom ends of the peppers, coring mechanism for the peppers disposed adjacent to and above the said cups, the coring mechanism comprising a rotatable coring head including a plurality of vertical reciprocable coring devices, means for imparting rotary movement to the said devices independently to that of the said head, the said coring devices including rotary coring tubes adapted to enter successively the peppers to be cored for removing the cores therefrom, hold-down means engaging the peppers immediately in advance of the coring tubes, resilient mountings for the hold-down means, means positioned interiorly of the coring tubes for separating the cores cut from the pepper by the coring tubes, means operable when the said coring devices have moved to predetermined points in their conveying travel to expel the cores, the said means including vertically reciprocable actuating instrumentalities for the core-separating means, vertically spaced cam tracks in the coring head, and operating means operatively engaging the cam tracks and the said instrumentalities for reciprocating the latter responsive to actuation of the coring tubes.

5. A pepper coring machine comprising an endless conveyor including a series of pepper-carrying cups, each cup being adapted to receive a pepper with the bloom end down, means in each cup adapted to remove the bloom end of the pepper carried by the cup, the said means comprising a rotary burr at the bottom of each cup, each cup being substantially shaped to embracingly receive the bloom end of a pepper, a coring device adapted to penetrate the pepper within each of the cups for decoring purposes, the said coring device also including hold-down means for engaging each pepper at its top in advance of but adjacent to its reaching the coring device, common drive means for the coring device and for the endless conveyor, rotary actuating means on each cup for the burr contained therein, and a guide track adjacent to the coring device but somewhat in advance thereof for frictionally engaging and rotating the actuating means for the burr as each pepper approaches the coring device, thereby removing the bloom end of each pepper immediately in advance of the coring device.

6. A machine for coring peppers comprising an endless conveyor including a series of pepper-carrying cups, each cup having a shape approximating the bloom end portion of the peppers and being adapted to embracingly contain a pep-

per with the stem of the pepper exposed and the bloom end down, coring mechanism positioned adjacent to and above the said cups, means for bringing each of the peppers into operative relation with the coring mechanism, cutting means adapted to remove the stems from the peppers, a burr device positioned at the bottom of each cup for removing the bloom end of the pepper in the cup, means extending from each cup for operating the burr device, the said coring mechanism including cutting means adapted to enter the pepper within each cup for decoring purposes, means for actuating the conveyor to successively position each cup in operative relation with the stem-removing cutting means in advance of the decoring means, and track means for frictionally engaging the burr operating device on each cup for removing the bloom end from the peppers as each cup approaches the decoring means.

7. A coring machine for removing cores from peppers or the like, which comprises, in combination, a machine frame, a rotatable coring head carried by the frame and including an annular series of coring tubes, an endless conveyor chain mounted on the machine frame, a plurality of pepper-receiving cups mounted on the endless conveyor chain for embracingly receiving peppers to be cored by the coring head, the said chains and cups thereon being arranged to pass beneath the head, means for vertically reciprocating the coring tubes for causing them to enter the pepper being cored, means for rotating the coring tubes during their penetration thereof into the pepper, a plurality of core-gripping fingers extending into the coring tube, cam means pivotally mounting the fingers on the coring tube, a cam rod connected to the coring tube and carrying the said tube, a finger control and core-ejecting rod mounted within the cam rod, means on the said control rod for predeterminedly operating the fingers first to close them to grip the core, and then after a predetermined interval to open the fingers to release the core, means mounted on the machine frame for actuating the cam rod and the finger-control and core-ejecting rod, the said means including upper and lower cam tracks, rollers on the said cam rod and finger-control and core-ejecting rod disposed to operate in the said cam tracks responsively to rotation of the coring head, and driving means on the machine frame for operating the coring head and the endless conveyor chain.

8. A pepper coring machine comprising in combination, an endless conveyor, a series of pepper-carrying cups operatively connected with the conveyor for receiving peppers with their bloom ends downward, the said cups being shaped to embracingly hold the bloom ends of the peppers, a machine frame, a vertical main drive shaft mounted in said frame, coring mechanism for the peppers disposed adjacent to and above the said cups carried by said shaft, the coring mechanism comprising a rotatable coring head including a plurality of vertical reciprocable coring devices, means for imparting rotary movement to the said devices independently to that of the said head, the said coring devices including rotary coring tubes adapted to enter successively the peppers to be cored for removing the cores therefrom, hold-down means engaging the peppers immediately in advance of the coring tubes, resilient mountings for the hold-down means, means positioned interiorly of the coring tubes for separating the cores cut from the

pepper by the coring tubes, said means including interiorly of each tube a pair of core gripping fingers pivotally attached to said tube adjacent their upper ends and formed with cam heads extending exteriorly of the tube, said cam heads being embraced by a resilient member normally retaining the fingers expanded against the tube wall, a member vertically reciprocal in said tube and coacting with said cam heads to bring the fingers into gripping relation with the core upon its separation from the peppers, said vertical reciprocal member being further operable to expel the core when the said coring devices have moved to predetermined points in their rotary travel, vertically spaced cam tracks in connection with said coring head, and operating means in connection with said vertical reciprocal coring devices engaging said cam tracks for reciprocating said reciprocal coring devices.

9. A coring machine for removing cores from peppers or the like, which comprises, in combination, a machine frame, a main vertical drive shaft rotatably mounted in the frame, suitably mounted on and attached to said drive shaft spaced from its upper end is an annular series of interconnected frame members forming a rotatable coring head, fixedly suspended from said machine frame are upper and lower tracks, said lower track being within the coring head, reciprocally mounted in each frame member of said series is a cam rod carrying at its upper end a cam roller adapted to supportingly travel in said upper track, said rod carrying at its lower end a rotatable coring tube, an endless conveyor mounted on the machine frame, a plurality of pepper receiving cups mounted on the endless conveyor for embracingly receiving peppers to be cored, the conveyor and cups thereon being arranged to pass beneath the head, means for rotating said head to effect rotary travel of said cam rods with respect to said track to effect vertical reciprocation of the coring tubes causing them to enter the respective peppers being cored, additional means for rotating the coring tubes during penetration thereof into the peppers as they pass beneath said coring head, a pair of core gripping fingers extending into each coring tube, cam means pivotally mounting the fingers on the coring tube, a finger control and a core-ejecting rod mounted within the cam rod and carrying a cam roller mounted for engagement with said lower track, means on the said control rod for predeterminedly operating the fingers first to close them to grip the core, and then after a predetermined interval to open the fingers to release the core, and driving means on the machine frame for operating the coring head and the endless conveyor.
